UNITED STATES PATENT OFFICE.

WILLIAM D. DAVIS, OF LOCKPORT, NEW YORK, ASSIGNOR TO JAMES R. ROWE AND E. D. DAVIS, OF LOCKPORT, NEW YORK.

BOX-NAILING PRESS.

SPECIFICATION forming part of Letters Patent No. 792,760, dated June 20, 1905.

Application filed October 11, 1904. Serial No. 228,063.

To all whom it may concern:

Be it known that I, WILLIAM D. DAVIS, a citizen of the United States, residing at Lockport, in the county of Niagara and State of New York, have invented a new and useful Improvement in Box-Nailing Presses, of which the following is a specification.

This invention relates to machines or presses for pressing down and holding the covers of filled boxes of fruit while the covers are being nailed on the box.

The boxes in which fruit such as apples, oranges, and lemons are shipped are ordinarily made of such thin boards that nailing strips or cleats extending across the ends of the bottom and cover-boards are required to prevent the boards from tearing away from the nails in handling the boxes. These cleats also serve when the boxes are piled up to hold bodies of the boxes out of contact, and thus relieve the fruit in the lower boxes from the weight of the superposed boxes. In packing the boxes they are usually filled so that the fruit projects above the top edge of the boxes, and in applying the cover or top boards they bear between the ends on the fruit, and the ends of the boards must be pressed down against the ends of the box and there held, together with the nailing-cleats, while the securing-nails are driven into place. It is thus a slow and tedious operation for one man to hold and nail the covers on the box.

The primary object of the invention is to provide a simple efficient press or machine for pressing down and holding the cover-boards in place while they and the nailing-cleats are nailed to the ends of the boxes whereby a single workman can cover the boxes rapidly and with the minimum labor.

Another object of the invention is to make the press adjustable to accommodate boxes of different sizes.

A still further object of the invention is to provide a press for the stated purpose of the novel construction hereinafter described, and set forth in the claims.

In the accompanying drawings, consisting of two sheets, Figure 1 is a side elevation of a box-nailing press embodying the invention.

Fig. 2 is a front elevation, partly in section, thereof with a box in place on the box-support which is shown in its lower position. Fig. 3 is a plan view thereof, partly in horizontal section, in line 33, Fig. 2. Fig. 4 is a longitudinal sectional elevation thereof, showing the box-support and box raised.

The machine or press comprises, briefly stated, a stationary frame, a vertically-sliding box support or frame on which the filled box is placed with the cover laid thereon, and a treadle by which the box-support is raised to lift the box up until arrested by the engagement of the cover-boards with stationary holding-rod, which press down the ends of the cover-boards and hold them in place until secured.

In the machine shown in the drawings the stationary frame comprises a base or platform A, upright corner-posts B, which are secured at their lower ends to angle-irons b on the base or are attached thereto in any other suitable manner; and top, front, and back cross-bars C and end bars C', which are secured to and connect the upper ends of the upright corner-posts. Angle-bars are preferably employed for the corner-posts and top cross-bars. The frame is also stiffened and strengthened by intermediate front and back cross-bars c and end bars c' and an upright bar c', which connects the top and intermediate back cross-bars. Sufficient space is left between the top and intermediate front cross-bars C c to enable the largest-sized box for which the machine is intended to be slipped into the frame between said bars, and the front corner-posts are preferably provided opposite this space with flaring guide-flanges d, which can be conveniently formed by cutting the front flanges of the corner-posts at the top and intermediate front cross-bars and turning out the portions of the flanges between the cuts.

The vertically-sliding box support or frame E is preferably made of wood and consists of upright corner-posts connected at their upper and lower ends by horizontal front, rear, and end cross-bars. The upper end bars e are adjustably attached to the upper front and rear

cross-bars e' , so that they can be moved toward and from each other and secured in the different positions required for boxes of different lengths. In the construction shown 5 the end bars e rest on top of the front and rear cross-bars e' and have secured thereto screw-clamps F, which embrace the front and rear cross-bars, to which they are clamped to secure the end bars by turning up the screws 10 of the clamps. Any other suitable securing devices can be employed in place of the screw-clamps. G represents guide-plates secured to the end bars e of the box-support for guiding the box into proper position in 15 the box-support when placing it in the machine. The guide-plates are preferably made of metal and have outwardly-flaring front ends. The box-support E is confined and guided in its movements in the stationary 20 frame by the flanged corner-posts of the latter.

H H represent presser-rod to bear on and press the ends of the cover-boards down on the ends of the box. The rods are arranged horizontally parallel with and above the end 25 portions of the box on the box-support and are supported by the front and rear top cross-bars of the stationary frame.

In the machine shown the front and rear cross-bars are provided with holes h , in which 30 the presser-rod are removably retained by cotter-pins h' or otherwise, this construction allowing the presser-rod to be held at different distances apart to properly operate upon boxes of different lengths.

35 The box-support E is operated by a suitable treadle I, that shown having a foot-board arranged in front of the stationary frame and side arms i , which are pivoted at their rear ends to the angle-irons b on the sides of the 40 platform. The treadle is connected to the sliding box-support by chains or the like flexible members K, which pass over pulleys k , journaled in any suitable manner on the sides of the stationary frame and have their 45 opposite ends attached, respectively, to the side arms of the treadle and hooks k' on the sides of the box-support. The upward movement of the treadle is limited by suitable stops k'' , fixed on the stationary frame. By engaging 50 the hooks k' on the box-support in different links of the chains K the box-support can be held at different elevations, the object being to have the tops of shallow and deep boxes at substantially the same elevation when the 55 box-support is lowered, so that the same length of movement of the treadle will lift the tops of the different boxes up against the presser-rod H.

60 L represents a spring connected at opposite ends to the platform and box-support for lowering the latter.

65 The operation of the machine is as follows: After the end bars e of the box-support and the presser-rod H have been adjusted to the length of the boxes to be covered and the

box-support adjusted to the proper height a filled box, with the cover-boards laid on top thereof, is placed on the box-support between the guide-plates G, as shown in Fig. 2. The bottom nailing-cleats of the box rest upon 70 the end bars e of the box-support, which being raised above the other portions of the box-support hold the bottom of the box up out of contact with the support, so that the bottom can give, and thus prevent the fruit 75 from being bruised by pressure when the cover-boards are pressed down. The operator then depresses the treadle I and raises the box-support and box until the presser-rod bear on and press the ends of the cover-boards 80 down against the ends of the box, as shown in Fig. 4. The nailing-cleats are then placed across the ends of the cover-boards against the presser-rod, which are so disposed as to constitute gages or rests for the nailing-cleats, 85 and the cover-boards secured by driving nails through the nailing-cleats and cover-boards into the ends of the box. As the presser-rod hold the cover-boards in place until nailed and also assist in holding the nailing-cleats, 90 an operator can nail the covers on the boxes with great rapidity and ease.

Means may be provided, if deemed desirable, for holding the box-support and box in their raised position, and thus relieve the operator from the exertion of holding down the treadle. The means shown for this purpose consist of toothed racks M, Fig. 2, fixed to the front corner-posts of the stationary frame beside the side arms of the treadle. The 100 teeth of both racks extend in the same direction, and to lock the treadle when down it is only necessary for the operator to slightly press the treadle over to one side by a lateral thrust of the foot, so that its side arms engage with the teeth of the racks. A slight lateral movement of the treadle in the opposite direction will disengage its arms from the rack-teeth and free the treadle. Any other suitable means may be employed for releasably holding the box-support in its raised position. 110

What I claim is—

1. The combination of a stationary frame having substantially parallel front and rear top bars, horizontal presser-rod which are adjustably secured at their opposite ends to said top bars and are adjustable toward and from each other on said horizontal bars of the frame to suit boxes of different lengths, a box-support movable vertically in said frame beneath the presser-rod, and means for raising said box-support and the box thereon so that the presser-rod bear on and press down the ends of the box-cover, substantially as set 120 forth.

2. The combination of a stationary frame, stationary horizontal presser-rod supported by and adjustable on said frame toward and from each other, a box-support movable ver- 130

- tically in said frame beneath the presser-rod
and having horizontal top bars, box-guides
adjustable toward and from each other on and
releasably secured to the horizontal top bars
5 of said box-support, and means for raising
said box-support and the box thereon so that
the presser-rod bear on and press down the
ends of the box-cover, substantially as set
forth.
- 10 3. The combination of a stationary rectangular frame having upright corner-posts connected at their upper ends by horizontal bars, horizontal pressure-rod secured to opposite horizontal bars of said frame, a vertically-
15 movable box-support confined between and guided in its vertical movements by said upright corner-posts, a box-guide on said box-support, and means for raising said box-support and the box thereon so that the presser-
20 rods bear on and press down the ends of the box-cover, substantially as set forth.

4. The combination of a stationary rectangular frame having upright corner-posts consisting of angle-bars, and horizontal bars connecting the upper ends of said corner-posts, 25 horizontal presser-rod secured to opposite horizontal bars of said frame, a vertically-movable box-support confined between and guided in its vertical movements by said upright corner-posts, and means for raising and 30 lowering said box-support, said corner-posts above the box-support when in its lowered position having portions of their flanges turned outwardly to form vertical guides for the box, substantially as set forth. 35

Witness my hand this 7th day of October,
1904.
